(57) **CLAIM**

The ornamental design for a pyramid handrail support, as shown and described.

DESCRIPTION

FIG. 1 is a top isometric view of a pyramid handrail support.

FIG. 2 is a bottom isometric view thereof.

FIG. 3 is a front elevational view thereof.

FIG. 4 is a back elevational view thereof.

FIG. 5 is a left elevational view thereof.

FIG. 6 is a right elevational view thereof.

FIG. 7 is a top plan view thereof.

FIG. 8 is a bottom plan view thereof; and,

FIG. 9 is a top isometric view thereof, shown in an alternate environment.

The broken lines shown in the figures illustrate environment and form no part of the claimed design.

1 Claim, 3 Drawing Sheets

FIG. 1***FIG. 2***

FIG. 7***FIG. 8******FIG. 9***
